UNITED STATES PATENT OFFICE

ROBERT L. McCARTY, JR., OF EDGEWOOD, PENNSYLVANIA

DESIGN FOR A FINGER RING

Application filed March 19, 1932. Serial No. 43,240. Term of patent 3½ years.

To all whom it may concern:

Be it known that I, ROBERT L. McCARTY, JR., a citizen of the United States, residing at Edgewood, in the county of Allegheny and State of Pennsylvania, have invented a new, original, and ornamental Design for Finger Rings, of which the following is a specification, reference being had to the accompanying drawing, forming a part hereof, in which

Figure 1 is a view in perspective of a finger ring embodying my new design,

Fig. 2 is a view in end elevation of the ring shown in Fig. 1, and

Fig. 3 is a top plan view of the ring shown in Fig. 1 as cut and unrolled into a plane.

I claim:

The ornamental design for a finger ring substantially as shown.

In testimony whereof, I have hereunto subscribed my name this 15th day of March, 1932.

ROBERT L. McCARTY, JR.
